UNITED STATES PATENT OFFICE.

CHARLES P. PETERSON, OF CHATTANOOGA, TENNESSEE, ASSIGNOR TO THE CAHILL IRON WORKS, OF SAME PLACE.

DESIGN FOR A GRATE.

SPECIFICATION forming part of Design No. 20,573, dated March 10, 1891.

Application filed November 22, 1890. Serial No. 372,379. Term of patent 7 years.

To all whom it may concern:

Be it known that I, CHARLES P. PETERSON, a citizen of the United States, and a resident of Chattanooga, in the county of Hamilton and

5 State of Tennessee, have invented and produced a new and original Design for Grates, of which the following is a full, clear, and exact description, reference being had to the accompanying drawing, which forms a part of 10 this specification.

My invention relates to a design for grates to be used in connection with open fire-places.

In the accompanying drawing, the figure represents a perspective view of a grate showing my design.

In the said drawing, the reference-numeral 1 designates the grate-bars, curved from front to rear, as shown, and 2 the grate-front. The grate-front near each end has two horizontal 20 openings 2^a and at the center three vertical openings 2^b. Interposed between these central and end openings are openings 3, formed by the diagonal bars 6, of substantially tri-

angular shape and arranged in the form of a Maltese cross. Upon the upper edge of the 25 front are provided a number of upwardly-extending triangular-shaped projections 7.

From the above, in connection with the drawing, it will be seen that I provide a grate which is very ornamental in appearance. 30

What I claim is—

The design for a grate, the same comprising the curved bars 1, the front 2, having the horizontal end openings 2^a, vertical central openings 2^b, the triangular openings 3, arranged in the form of a Maltese cross, and the upwardly-extending projections 7, substantially as shown and described. 35

In testimony that I claim the foregoing as my own I have hereunto affixed my signature 40 in presence of two witnesses.

CHARLES P. PETERSON.

Witnesses:

FRANK SMITH,

E. W. MOUNTCASTLE.
